UNITED STATES PATENT OFFICE.

RAGNAR ANDERSON, OF SHERIDAN, WYOMING.

SALT AND PEPPER SHAKER.

1,351,602.

Specification of Letters Patent. Patented Aug. 31, 1920.

Application filed May 11, 1920. Serial No. 280,630.

To all whom it may concern:

Be it known that I, RAGNAR ANDERSON, a citizen of Sweden, residing at Sheridan, in the county of Sheridan and State of Wyoming, have invented new and useful Improvements in Salt and Pepper Shakers, of which the following is a specification.

This invention relates to condiment holders, particularly to those of the combined type, and has for its object the provision of a condiment holder which is formed of duplicate sections, one adapted to hold pepper and the other adapted to hold salt.

An important object is the provision of a device of this character in which the holes permitting shaking out of the condiment are normally closed, the device being provided with means whereby these holes may be opened when desired.

A further object is the provision of a device of this character which is so constructed that the size of the holes may be varied.

An additional object is the provision of a device of this character which will be simple and inexpensive in manufacture, highly efficient in use, durable in service, and a general improvement in the art.

With the above and other objects and advantages in view, the invention consists in the details of construction to be hereinafter more fully described and claimed and illustrated in the accompanying drawings in which—

Figure 1 is a side elevation of the device, Fig. 2 is a longitudinal sectional view through one end thereof.

Fig. 3 is a plan view of one end, and

Fig. 4 is a fragmentary detail view showing the adjusting mechanism.

Referring more particularly to the drawings, the numeral 10 designates the body of the device which is formed as a shell of metal, glass, porcelain, or other suitable material, and the shell may be of any suitable shape though in the present instance it is shown as having substantially the same shape as an egg cup. This shell is divided transversely into two compartments by a partition 11 and the construction at both ends being the same, it is believed that a detailed description of one end will suffice.

Detachably engaged upon each end of the shell, as by threading, is a cap 12 formed with a channel or bead 12^a provided in one side with slots 13 and 13^a. The cap is provided in its top with a plurality of arcuate

slots 14. Disposed against the underside of the cap 12 and pivotally connected therewith, as by means of a rivet 15, is a disk 16 having a plurality of arcuate slots 17 therein adapted to be brought into registration to a greater or less extent with the slots 14.

Extending from one side of the disk 16 is a lug 18 which is movable through the slot 13 in the cap and secured to this lug 18 is a curved rod 20 disposed within the beads 12^a. Slidably adjustable within the bead 12^a is a curved plate 19 having an apertured ear 19^a through which the rod 20 is slidable. The rod 20 is offset, as shown at 20^a, to lie against the cap and form a closure for the slot 13. The lug 18 of course passes through the rod. A coil spring 21 surrounds the rod 20 between the lug 18 and the ear 19^a for normally holding the disk 16 in such position that the slots 17 therein will be out of registration with the slots 14. A screw 22 passes through the slot 13^a into the plate 19 for holding the plate in adjusted positions for varying the distance between the lug 18 and end of the plate 19 so that when the lug 18 is moved, the slots 17 and 14 may be brought to a greater or less extent into registration, as will be readily apparent.

In the operation of the device it will be seen that ordinarily the slots 14 are closed by the disk 16. When it is desired to shake out a condiment the device is disposed with the proper end up and the operator engages his thumb against the proper one of the lugs 18 and moves it in opposition to the spring 21 whereby to rotate the disk to bring the slots 17 therein in registration with the slots 14, whereupon the condiment may be shaken out in the ordinary manner. When pressure upon the lug 18 is relieved the disk 16 will be returned to normal position, closing the slots.

From the foregoing description and a study of the drawings it will be apparent that I have thus provided a simply constructed and easily operated device which will be very convenient in use as both salt and pepper may be contained within the same shell or receptacle and shaken out selectively as desired.

While I have shown and described the preferred embodiment of my invention, it is of course to be understood that I reserve the right to make such changes in the form, construction, and arrangement of parts as will

not depart from the spirit of the invention or the scope of the subjoined claims.

Having thus described my invention, I claim:

- 5 1. A condiment holder comprising a shell divided transversely into two compartments which are similar, a cap detachably engaged upon each end of the shell and provided in one side with a slot, the cap being further 80
- 10 provided with a plurality of series of arcuate slots, a disk disposed against the inner side of each cap and pivotally connected therewith for rotatable movement, the disk being provided with a plurality of series of 35 arcuate slots adapted to be brought into registration with said first named slots, a lug extending from the disk and passing through said first named slot, an apertured guide carried by the cap, a rod connected with the lug and slideable through said guide, a coil spring 40 surrounding the rod between the lug and guide, said guide including a curved plate disposed against the inner side of the cap and having an apertured bar against which said 45 spring abuts, said cap being provided with a second slot opposite said curved plate, and a screw passing through said last named slot and into said curved plate.
- 25 2. A condiment holder comprising a shell

divided transversely into two compartments which are similar, a cap detachably engaged upon each end of the shell and provided in one side with a slot, the cap being further 80 provided with a plurality of series of arcuate slots, a disk disposed against the inner side of each cap and pivotally connected therewith for rotatable movement, the disk being provided with a plurality of series of arcuate 35 slots adapted to be brought into registration with said first named slots, a lug extending from the disk and passing through said first named slot, an apertured guide carried by the cap, a rod connected with the lug and slideable through said guide, a coil spring 40 surrounding the rod between the lug and guide, said guide including a curved plate disposed against the inner side of the cap and having an apertured bar against which said 45 spring abuts, said cap being provided with a second slot opposite said curved plate, and a screw passing through said last named slot and into said curved plate.

In testimony whereof I affix my signature. 50

RAGNAR ANDERSON.
